(57) **CLAIM**

The ornamental design for a sign holder, as shown and described.

DESCRIPTION

FIG. 1 is a front perspective view of the sign holder illustrating the new design;

FIG. 2 is a front view of the sign holder illustrated in FIG. 1 which is a mirror image of the rear view;

FIG. 3 is an enlarged left-side view of the sign holder shown in FIG. 1 which is mirror image of the right-side view.

FIG. 4 is a sectional view of the sign holder shown in FIG. 1, taken along line 4-4 on FIG. 2.

FIG. 5 is a top view of the sign holder shown in FIG. 1;

FIG. 6 is a bottom view of the sign holder shown in FIG. 1; FIG. 7 is a front perspective view of a second embodiment of the sign holder;

FIG. 8 is a front view of the sign holder shown in FIG. 7;

FIG. 9 is a rear view of the sign holder shown in FIG. 7;

FIG. 10 is an enlarged left-side view of the sign holder shown in FIG. 7;

FIG. 11 is a sectional view of the sign holder shown in FIG. 7, taken along line 11-11 on FIG. 8.

FIG. 12 is a top view of the sign holder shown in FIG. 7; and, FIG. 13 is a bottom view of the sign holder shown in FIG. 7.
